UNITED STATES PATENT OFFICE.

EMRY J. DUNKLEE, OF HACKENSACK, NEW JERSEY.

MACHINE FOR RENAPPING AND REFINISHING CLOTH.

1,164,482.

Specification of Letters Patent. Patented Dec. 14, 1915.

Application filed April 28, 1915. Serial No. 24,475.

To all whom it may concern:

Be it known that I, EMRY J. DUNKLEE, a citizen of the United States, and a resident of Hackensack, in the county of Bergen 5 and State of New Jersey, have invented a new and Improved Machine for Renapping and Refinishing Cloth, of which the following is a full, clear, and exact description.

This invention relates to a machine for 10 renapping and refinishing worn cloth, and is especially adapted for use by tailors and cleaners whereby woolen garments can at the worn spots be so treated as to give the garment a new appearance.

15 The general objects of the present invention are to provide a reliable, easily operated and efficient machine of the character referred to which is adapted to be rolled over the worn portion of a fabric garment 20 so as to provide a nap and thereafter trim the same to be uniform with the nap of the unworn portions, there being an electrically heated ironing roller associated with the cutter so that the fabric can be 25 pressed where it is renapped and refinished.

A further object of the invention is the provision of a device which is adapted to be operated by hand by being rolled over the parts to be renapped and refinished, the 30 device embodying means for adjusting the napping brush and the cutter, whereby the machine can produce nap of any length so as to match the unworn parts of the garment, and furthermore, the machine embodies an electric motor which, by means 35 of clutch devices, can be operatively connected with either the napping brush or the cutter for rotating the same.

With such objects in view, and others 40 which will appear as the description proceeds, the invention comprises various novel features of construction and arrangement of parts which will be set forth with particularity in the following description and 45 claims appended hereto.

In the accompanying drawings, which illustrate one embodiment of the invention and wherein similar characters of reference indicate corresponding parts in all the

views, Figure 1 is a vertical longitudinal 50 section of the machine; Fig. 2 is a side view thereof; Fig. 3 is a transverse section on the line 3—3, Fig. 1; Figs. 4, 5 and 6 are detail sectional views respectively on the lines 4—4, 5—5, 6—6, Fig. 1; Fig. 7 is a detail 55 sectional view of the adjustable fixed cutter bar associated with the rotary cutter; and Fig. 8 is a diagrammatic view of the circuit connections.

Referring to the drawing, A designates 60 the casing or housing of the machine, which housing is preferably, although not necessarily, a metal structure closed at all points except the bottom from which partially protrude the electrically heated ironing roller 65 B, the renapping brush C and the rotary cutter D, which is located at the side of the ironing roller B opposite from the renapping brush C. In the casing is a box 70 E of inverted U-shape cross-section, as shown in Fig. 4, the ends of the box being fastened to the end walls 1 of the casing A. Supported on the top of this box is an electric motor F which supplies the power 75 for rotating the brush and cutter. In use the machine is moved back and forth over the goods to be renapped and refinished, the weight of the machine being sustained by the roller B, and to facilitate the movement of the machine the opposite ends of the casing 80 are provided with handles G.

The ironing roller B comprises an inner drum 2 which has applied to its circumferential surface an electric heating element, such as a wire 3, suitably insulated from the 85 drum. The roller has a shell surrounding the inner drum, such shell consisting of a cylinder 4 and heads 5. The cylinder 4 is larger in diameter than the diameter of the wire winding 3, so that the wire will not 90 be in electrical contact with the shell of the ironing roller but the heat from the current passing through the winding 3 will be transmitted to the cylinder 4 through the slight intervening air gap 6. The ironing 95 roller B is set into the box E and the opposite walls of the latter have supports in the form of screws 7 which screw into the hub

bosses 8 of the inner drum. The heads 5 of the outer drum or shell have bearing openings 9 which fit around the hub extensions 8, so that the outer drum or shell will 5 be free to rotate while the inner drum is stationary. Current is supplied to the winding 3 by leading-in wires 10 which pass into the inner drum through one of the bearing screws 7. The electrically heated roller B 10 is disposed in a chamber by itself so as to conserve the heat, the walls and top of the chamber being, as shown in Fig. 1, lined of pieces of asbestos 11 or equivalent material.

The napping brush C is arranged with its 15 axis horizontal or parallel with the axis of the roller B, and consists of a cylindrical body 12 having steel wire bristles 13 of any desired shape or stiffness. The cylinder has a shaft 14, the ends of which are journaled 20 in bearing blocks 15 fastened to the side walls of the box E. One end of the shaft protrudes out of the box and has a pulley 16 around which a belt 17 passes. This belt also passes around a pulley 18 on the shaft 25 19 of the motor F. Adjacent the brush C is a parallel gage roller 20 which can be set for governing the depth of penetration of the brushing needles into the cloth to be renapped. The gage roller 20 has its ends 30 supported in adjustable bearings 21, Fig. 4, which are slideable in guide frames 22 and are adjustable by screws 23 journaled in the frames and have a threaded connection with the bearings 21. These screws are simultaneously rotated so that both ends of the gage 35 roller will be moved to the same extent. The turning of the screws is accomplished by a horizontal shaft 24 provided on its outer end with a handle 25, and on this shaft are 40 worms 26 which mesh with worm gears 27 on the screws 23. When the brush is in use, as shown in Fig. 1, the rollers B and 20 will rest on the fabric, and as the machine is moved over the worn part of the fabric the 45 brush, which rotates at a suitable speed, will tear out or loosen the fibers to form a new nap.

The rotary cutter D comprises spiral knives 28 fastened to the heads 29 of a spool 50 30, which spool is fastened to a shaft 31 that carries a pulley 32. Passing around this pulley is a belt 33 which also passes around a pulley 34 on the motor shaft. The cutter 55 is secured by said screws 35 to the shaft, 55 which latter is journaled in bearing blocks 36 fastened to the side walls of the box E. By taking out the screws the shaft can be removed and the rotary cutter taken out of the machine. The brush C is also removable 60 from its shaft in the same manner, whereby brushes of different types may be interchanged. The knives 28 of the cutter coöperate with a cutting bar 37 which is fastened to bearing blocks 36 and extends

horizontally of and under the rotary cutter 65 D, the relation of the cutting bar and knives being similar to a lawn mower construction. This cutter bar 37 has its edge 37', Fig. 7, adjustable toward and from the knives, the adjustment being effected by means of screws 70 38 and 39, whereby horizontal and vertical adjustments are provided. In making these adjustments the securing bolts 40 are loosened, and after the proper adjustments are obtained these bolts are tightened. Co- 75 operating with the rotary cutter D is a gage roller 41 which is adjustably mounted like the roller 20, whereby the relation of the cutter to the fabric to be refinished can be regulated. 80

In use the brush C and cutter D are used independently, and therefore a clutch device is employed to connect either one of these elements with the motor. This clutch device comprises teeth 42 on the motor shaft 85 19 and teeth 43 and 44 on the pulleys 18 and 34 which are spaced apart on the motor shaft. The pulleys have grooves 45 into which engages a forked shifting member 46 fastened to a horizontally movable bar 47 90 which is slideable on and transversely of the top of the box E. When the parts are in the position shown in Fig. 3 the pulley 18 is clutched to the motor shaft so that the brush C will be operated, and by moving the controlling rod 47 to the right, Fig. 3, the pulley 34 will be clutched to the motor shaft so that the cutter will be operated. This controller rod 47 has a handle 48 which extends out of the casing A so as to be operable. The controlling rod is held in either of its positions by a spring clutch 47' engageable in openings 47^a in the rod 47. This spring catch automatically engages and disengages as the rod 47 is pushed in or pulled out. On 95 the casing are electrical switches 49 and 50 which connect the motor F and heating element or winding 3 independently to a source of current supply, as shown in Fig. 8. It will be understood that the switch 50 is 100 closed only when the ironing roller B is to be used for pressing the fabric after it has been renapped and refinished, and during the use of the napping brush and the rotary 105 cutter the roller B simply acts as a support 110 for the machine, the heating current being cut off.

From the foregoing description taken in connection with the accompanying drawings, the advantages of the construction and method of operation will be readily understood by those skilled in the art to which the invention appertains, and while I have described the principle of operation, together with the device which I now consider to be 120 the best embodiment thereof, I desire to have it understood that the device shown is merely illustrative and that such changes 125

may be made when desired as fall within the scope of the appended claims.

Having thus described my invention, I claim as new and desire to secure by Letters 5 Patent:

1. A machine for renapping and refinishing worn fabrics, comprising a supporting structure, a rotary brush on the structure for renapping the fabric, a cutting means 10 mounted on the structure for trimming the nap of the fabric, and means for movably supporting the machine on the fabric to be renapped and refinished.
2. A machine for renapping and refinishing worn fabrics, comprising a supporting structure, a rotary brush on the structure for renapping the fabric, a cutting means 15 mounted on the structure for trimming the nap of the fabric, and a heating roller disposed between the cutting means and brush on which the structure tilts for throwing either the cutting means or brush into contact with the fabric while the roller runs over the same, and gage devices associated 20 respectively with the brush and cutting means.
3. A machine adapted to run over worn fabric for renapping and refinishing the same, said machine comprising a supporting 25 structure, an ironing roller mounted thereon, and on which the structure is tilttable, renapping and cutting means mounted on the structure at opposite sides of the roller, a motor for both of said means, and a clutch 30 device for connecting either of said means with the motor.
4. A machine adapted to run over worn fabric for renapping and refinishing the same, said machine comprising a supporting 35 structure, an ironing roller mounted thereon and on which the structure is tilttable, renapping and cutting means mounted on the structure at opposite sides of the roller, a motor for both of said means, a clutch device 40 for connecting either of said means with the motor, and gages mounted on the structure and disposed adjacent to and outwardly from the cutting and renapping means.
5. A machine for renapping and refinishing worn fabric, comprising an element 45 forming a roller support for the machine and including electrical heating means for converting the element into an iron, and independent cutting and renapping means 50 mounted on the structure to act on the fabric over which the said element rolls, and gage means coöperating with the element to regulate the action of the renapping or cutting means on the fabric.
6. A renapping and refinishing machine 55 for worn fabrics, comprising a supporting structure, a motor thereon, a rotary element forming a supporting roller adapted to run over the fabric to be treated, an elec-

tric heater in the roller, separate switches 65 for connecting the motor and heater in circuit with a source of supply, a renapping device driven by the motor, and a cutter driven by the motor.

7. A renapping and refinishing machine 70 for worn fabrics, comprising a supporting structure, a motor thereon, a rotary element forming a supporting roller adapted to run over the fabric to be treated, an electric heater in the roller, separate switches for 75 connecting the motor and heater in circuit with a source of supply, a renapping device driven by the motor, a cutter driven by the motor, and a clutch for operatively connecting the motor with either the cutter or re- 80 napping device.

8. A machine of the class described comprising a casing open at its bottom, an open-bottom box secured in the casing, a motor mounted on the box, an ironing and supporting roller journaled in the box and projecting out of the bottom thereof, a rotary renapping brush mounted in the box at one side of the roller, a rotary cutter mounted in the box at the opposite side of the roller 90 from the brush, and controllable driving connections extending between the motor and the brush and cutter, whereby either of the latter may be independently operated.

9. A machine of the class described comprising a casing open at its bottom, an open-bottom box secured in the casing, a motor mounted on the box, an ironing and supporting roller journaled in the box and projecting out of the bottom thereof, a rotary 100 renapping brush mounted in the box at one side of the roller, a rotary cutter mounted in the box at the opposite side of the roller from the brush, independent driving means between the motor and brush and cutter, 105 and a controller for throwing one operating means into action and the other out of action, said controller and driving means being housed in the casing.

10. A machine of the class described comprising a casing open at its bottom, an open-bottom box secured in the casing, a motor mounted on the box, an ironing and supporting roller journaled in the box and projecting out of the bottom thereof, a rotary renapping brush mounted in the box at one side of the roller, a rotary cutter mounted in the box at the opposite side of the roller from the brush, controllable driving connections extending between the motor and the brush and cutter, whereby either of the latter may be independently operated, and means surrounding the roller to prevent 115 radiation of heat.

11. A machine adapted to run over a worn 120 fabric for renapping and refinishing the surface thereof, said machine comprising a supporting structure, a roller mounted thereon

and on which the machine moves on the fabric, and renapping and cutting means mounted on the structure.

12. A machine adapted to run over a worn fabric for renapping and refinishing the surface thereof, said machine comprising a supporting structure, roller means mounted on the structure and by which the same moves over the fabric, and separate renapping and

cutting means mounted on the structure and spaced apart.

In testimony whereof I have signed my name to this specification in the presence of two subscribing witnesses.
